UNITED STATES PATENT OFFICE.

ANTON HASLINGER, OF ROCKLEDGE, PHILADELPHIA, PENNSYLVANIA.

AUTOMATIC CUT-OFF FOR STOP COCKS.

Application filed October 5, 1927. Serial No. 224,192.

The present invention relates to automatic cut-offs for stop cocks, thermostatically and electrically controlled, and the purpose of the invention is to provide a stop cock including a valve under tension in order to hold the valve in a normally closed position, with mechanical means for holding the valve open to permit the passing of fluid through the valve, which fluid may be water, oil or the like, there being an electrically controlled member, of which its circuit may be thermostatically closed, whereby the mechanical means may be released allowing the valve to automatically close and thereby cut off the passage of fluid.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:

Figure 1—is a view in elevation of a piping including a valve, for the conduction of a fluid, in the present instance it being gas, to be transmitted to a burner of a heater, and showing the means for mechanically holding the valve open, and the electrical means thermostatically controlled for releasing the valve lever permitting the valve to close, to shut off the flow of the fluid.

Figure 2—is an enlarged detailed view of the mechanical means including the valve lever for holding the valve open.

Figure 3—is an enlarged sectional view on line 3—3 of Figure 2.

Figure 4—is a view in elevation of the side opposite to that shown in Figure 1.

Figure 5—is an end elevation of Figure 4.

Referring to the drawings, 1 identifies a heater which may be any conventional type and 2 a burner and 3 a pipe line leading to the burner for the conduction of a fluid, such as gas to the burner. The pipe line 3 has a conventional type of valve 4 for permitting the entrance of the gas to the burner, said valve comprising a casing 5 and a valve proper 6. The valve proper 6 has a handle 7 rotating therewith provided with a gravity pawl 8 pivotally mounted thereon.

The valve proper 6 has a stem 9 projected at one end with a band spring 10 wound

around the stem for tensioning the same, one end of the spring being connected to the stem as at 11, and the other end to a projecting pin or lug 12, so as to adapt the spring to hold the valve in a normally closed position.

A bracket 13 of U form is secured to the pipe line as at 14 and it carries a flange 15 having an inclined edge 16 provided with a shoulder 17, with which the pawl 8 engages to hold the lever of the valve in such a position as to retain the valve in an open position, thereby permitting the gas to flow to the burner.

The bracket 13 carries a pair of electro-magnets 18, which are designed to attract an armature 19, which is so positioned pivotally as at 20, that when attracted it engages with the gravity pawl 8 and disengages it from the shoulder, hence releasing the lever and the valve and allowing the valve to move to a closed position thereby shutting off the flow of gas or other fluid through the pipe line.

The electro-magnets are in circuit with a battery 21 by means of a wire or lead 22, while the battery is in turn in circuit with a thermostatically operated circuit closure 23 similar in construction to that disclosed in the patent to Anton Haslinger of August 9th, 1921, Patent No. 1,387,050, which in turn is so positioned relative to the heater, that as the temperature of the heater increases, an expandable member 24 is expanded to engage with a contact for closing the circuit, energizing the electro-magnets attracting the armature which engages with the pawl and hence disengages it from the shoulder and releases the lever and due to the valve being under tension the valve automatically rotates to a closed position and shuts off the flow of gas to the burner. When the heater decreases in temperature the lever may again be set in its operative position, turning on the flow of gas, in which the burner may be lighted again, and thereby effecting the operation of the heater.

The casing of the heater is in circuit with the contact of the thermostatic control. The casing of the heater is also in circuit with the pipe line, and movable with the valve stem is a cam 26, which normally engages with a movable spring contact 27 for causing it to engage with the stationary contact 28, the latter being in circuit with the electro-magnets through the medium of a wire or lead 29. A suitable housing 30 is supported on the

bracket in any suitable manner, for instance by means of a screw 31, to protect the electro-magnets against injury.

The invention having been set forth, what is claimed is:

1. In a device for the purpose indicated the combination with a movable member having a gravity pawl, of an armature and a support for pivotally supporting the armature, the support having a shoulder with which the gravity pawl engages for retaining the member in one position, an electric circuit including electro-magnets, and means thermostatically controlled and in the circuit for energizing the magnets to attract the armature, which disengages the pawl from the shoulder and permits the release of the member.
2. In a device as set forth, a pivotally mounted movable member, a bracket, an electric circuit with electromagnets for the bracket, the electro-magnets being supported by the bracket, an armature carried movably by the bracket, means for operatively and disengagingly connecting the pivotally movable member with the bracket to hold said member

in one position, thermostatically controlled means in the circuit for closing the circuit and energizing the magnets which in turn attract the armature to actuate said operatively and disengagingly connecting means, to release 30 the pivotally movable member.

3. In a device for the purpose indicated, a pivotally movable member, a shut-off device to be actuated by said member, a bracket, a pair of magnets supported thereby and including an electric circuit, an armature pivotally supported on the bracket, the bracket having a shoulder, a gravity pawl carried by the pivotally movable member to engage with the shoulder to hold the member set with the 35 shut-off device open, and means in the circuit thermostatically operated for closing the circuit attracting the armature which in turn engages with the pawl and disengages the latter from the shoulder, thereby releasing the pivotally movable member.

In testimony whereof he affixes his signature.

ANTON HASLINGER.
